UNITED STATES PATENT OFFICE.

EDWARD WRIGHT, OF BROOKLYN, NEW YORK.

ROAD-SCARIFIER.

986,113.

Specification of Letters Patent.

Patented Mar. 7, 1911.

Application filed June 9, 1910. Serial No. 565,941.

To all whom it may concern:

Be it known that I, EDWARD WRIGHT, a subject of the King of Great Britain, residing at Brooklyn, in the county of Kings and State of New York, have invented certain new and useful Improvements in Road-Scarifiers, of which the following is a specification.

This invention comprises an improved form of road scarifier, the details and advantages of which will be pointed out in the following specification, taken in connection with the accompanying drawing, in which,—

Figure 1 is a side elevation of the scarifier; Fig. 2 is a top plan view of the same; Fig. 3 is a central vertical section through the same taken transversely of the shaft; and, Fig. 4 is a front elevation of the machine.

Referring to the drawing, 1 and 2 indicate suitable supporting wheels which carry a shaft 3, the main portion of which shaft, between the wheels, is rectangular in cross section. Secured to this shaft by bolts 4, one of which is shown in Fig. 3, is a heavy metal body A, of segmental form, carrying two sets of picks 5 and 6, respectively, one set of picks being arranged substantially at right angles to the other. The body A, which is cast in one piece, comprises two flat walls 7 and 8 arranged at right angles to one another and connected at their meeting ends by a short diagonal wall 9 through which the bolts 4 extend to connect the body with the axle. The walls 7 and 8 are alike, each being of T-shape, as shown in Fig. 4, the inner portions of the walls extending between the wheels while the outer portions 7^a and 8^a project laterally over the peripheries of the wheels and are thickened, as shown in Fig. 3, to form heavy and substantial transverse bars to receive the picks 5 and 6. These bars are provided with suitable tapering openings into which the picks are driven. The walls 7 and 8 are connected by side walls 9 and 10, and a wall 11, concentric with the axis of the shaft, connects the walls 7, 8, 9 and 10, forming an enclosure a, which serves the purpose of a tool box, or a box for holding picks. The wall 11 has an opening 12 and a suitable cover (not shown) may be connected to lugs 13 on the wall 11 for closing the tool box. The bars 7^a and 8^a are connected by a series of curved ribs 14.

As the heavy metal body A is secured to the shaft 3 at some distance from the center

of mass of said body, a large part of the weight of the body will rest upon one or the other set of picks according to whether the body is in the position shown in Figs. 1 and 3 or whether the body is turned about the shaft 3 as an axis until the picks 6 engage the ground.

The draw bar B has arms 15 journaled upon the ends of the shaft 3 and this draw bar may be swung about the shaft from the position shown in Fig. 1 to that shown in Fig. 3 when it is desired to reverse the direction of movement of the scarifier. When the scarifier is moving in the direction of the arrow, Fig. 1, the picks 5 will engage the ground and the draw bar will be in the position shown. When it is desired to reverse the movement, the body A will be swung about the shaft as a center, until the center of mass of the body passes the vertical plane of the shaft, when the body will drop heavily on the other side of the shaft and drive the picks 6 into the ground. The draw bar is then swung over the body and attached to the traction engine or other motive power and the scarifier pulled in the opposite direction. The body may be tilted over the vertical plane of the shaft manually, or by the pull of the traction engine exerted through a chain thrown over the rear ends of one or more of the uppermost picks. When the chain is used, it will slip off of the picks after the body has been tilted. Stops 16, integral with the walls 7 and 8, are provided for the purpose of limiting the depth to which the picks penetrate when the body is thrown over the center and also to limit the depth of penetration when the scarifier is in operation. These stops, as shown, are projections from the walls 7 and 8, the outer surfaces of such projections being rounded or semi-cylindrical in sections taken transversely of the machine, the purpose of this rounding of the stop being to permit the scarifier to turn at an angle to a straight course without having the stop dig into the ground. In transporting the scarifier from place to place, the lower picks may be removed and the body will then be supported upon the adjacent stop and will travel with little friction and without tearing up the ground.

The picks are double ended and four-cornered, and the openings in the bars are formed to receive either end of a pick and present one corner of the pick to the road-

way as a cutting edge. By reversing and rotating the picks, eight cutting edges on each may be availed of.

It will thus be seen that the scarifier, as a whole, is of very simple construction and is readily reversible, and that the tilting of the body, to reverse the machine, causes the picks to be driven into the road-way by the weight and impetus of the body. The arrangement of the pick supporting bars at approximately 90 degrees apart permits of the ready removal or insertion of picks in the bar which may be at any time in the vertical position.

15. What I claim is:—

1. A road scarifier, comprising a metal body, wheel-supported means for pivotally supporting the body upon a horizontal axis at one side of a vertical line passing through 20 its center of mass, so that said body is normally unbalanced upon the shaft, a set of picks carried by said body and adapted to engage the ground when its center of mass is at one side of said horizontal axis, and 25 another set of picks carried by said body and adapted to engage the ground when its center of mass is at the opposite side of said horizontal axis.

2. A road scarifier comprising a wheel-supported shaft or axle, a metal body connected, at one side of a vertical line passing through its center of mass, to said shaft and mounted thereon so that it may be tilted over the shaft from one side to the other, 35 and picks carried by said body for engaging the ground when the center of mass of the body is at one side or the other of the shaft.

3. A road scarifier comprising a wheel-supported shaft or axle, a metal body connected at one side of a vertical line passing through its center of mass, to said shaft, so that said body is normally unbalanced on 40 said shaft, said body having two sets of picks arranged at right angles to one another.

4. A road scarifier comprising a wheel-supported shaft or axle, a metal body connected at one side of its center of mass to said shaft and having pick-supporting bars arranged approximately ninety degrees 50 apart with respect to the axis of said shaft.

5. A road scarifier comprising a wheel-supported shaft or axle, a metal body having two walls or arms arranged substantially at right angles to one another and connected 55 to said axle adjacent to their meeting points, and picks carried by each of said walls.

6. A road scarifier comprising a wheel-supported shaft or axle, a metal body connected at one side of its center of mass to said shaft and having bars or arms for supporting two sets of picks, and stops projecting from the body adjacent to said bars adapted to limit the penetration of the picks and to rest upon the ground when the picks are removed.

7. A road scarifier comprising a wheel-supported shaft or axle, a metal body having pick-supporting bars arranged approximately ninety degrees apart with respect to said axle and stops on said body adjacent to 70 the picks for limiting the penetration of the picks.

8. A road scarifier comprising a wheel-supported shaft or axle, a metal body having pick-supporting bars arranged approximately ninety degrees apart with respect to said axle, and stops on said body adjacent to the picks for limiting the penetration of the picks, said stops having rounded outer surfaces.

9. A road scarifier comprising a wheel-supported shaft or axle, a metal body having two walls extending transversely of the machine and arranged at an angle to one another and connected to the axle adjacent to their meeting points, picks at the outer ends of said walls, and ribs connecting said walls.

10. A road scarifier comprising a wheel-supported shaft or axle, a metal body having two walls extending transversely of the machine and arranged at an angle to one another and connected to the axle adjacent to their meeting points, picks at the outer ends of said walls, side walls connecting with said transverse walls and a wall connecting said transverse and side walls, said latter wall having a doorway or opening therein.

11. A road scarifier comprising a wheel-supported shaft, a metal body connected at one side of its center of mass to said shaft and having two sets of picks arranged at angles to one another, and a draw bar having arms journaled upon the shaft.

In testimony whereof I affix my signature, in presence of two witnesses.

EDWARD WRIGHT.
